SEALING FLAP FOR GARMENT OPENINGS

Mario Di Paolo, Natick, Mass., assignor to the United States of America as represented by the Secretary of the Army

Filed Sept. 4, 1962, Ser. No. 71,567

Term of patent 14 years

(Cl. D3—26)

(Granted under Title 35, U.S. Code (1952), sec. 266)

FIGURE 1 is a top plan view of a sealing flap for garment openings embodying my new design;

FIGURE 2 is an end elevational view thereof;

FIGURE 3 is a side elevational view of the same; and

FIGURE 4 is a front elevational view on a reduced scale of the invention as it appears in wearing position without the garment to which it is attached. The broken line showing of the buttons is for illustrative purposes only.

The invention described herein, may be manufactured and used by or for the Government for governmental purposes, without the payment to me of any royalty thereon.

I claim:

The ornamental design for a sealing flap for garment openings, substantially as shown and described.
